SUCTION CLEANER

Willis F. Hudson, Riverside, Ill., assignor to The
Hoover Company, North Canton, Ohio, a cor-
poration of Ohio

Application December 23, 1933, Serial No. 703,687

5 Claims. (Cl. 15—8)

The present invention relates to suction cleaners in general and particularly to new and novel improvements in the construction of the suction cleaner nozzle. More specifically the invention 5 comprises the provision of a suction cleaner in the nozzle of which is provided a surface-contacting movable lip under which cleaning air passes and which is so positioned as to contact that portion of the surface-covering undergoing 10 cleaning which is lifted from the supporting surface and in which the pile is spread apart.

It is an object of the present invention to provide a new and improved suction cleaner. It is a further object of the invention to provide 15 a new and improved suction cleaner nozzle relationship. It is still another object of the invention to provide a suction cleaner in which a movable lip separates a high suction nozzle from a low suction nozzle. Still another object is the 20 provision in a suction cleaner of a high suction nozzle, a low suction nozzle, a movable nozzle lip between said nozzles, a positively driven agitator being positioned within the low suction nozzle. A still further object of the invention is 25 the provision of a suction cleaner in which a high suction nozzle is positioned immediately adjacent a low suction nozzle, the two nozzles having a common surface-contacting lip which is resiliently urged into contact with the surface 30 covering undergoing cleaning, and under which cleaning air passes in the operation of the machine. These and other more specific objects will appear upon reading the following specification and claims, and upon considering in connection therewith the attached drawing to which 35 they relate.

Referring now to the drawing to which a preferred embodiment of the invention is disclosed:

Figure 1 is a side view of a modern suction 40 cleaner embodying the present invention, certain parts being broken away;

Figure 2 is a partial bottom view of the nozzle shown in the cleaner of Figure 1;

Figure 3 is a partial section upon the line 3—3 45 of Figure 2 showing the movable nozzle lip;

Figure 4 is a view in perspective of the spring element which cooperates with the movable nozzle lip;

Figure 5 is a view in perspective of the movable 50 nozzle lip removed from the cleaner.

In the modern suction cleaner the suction-creating means function to lift the surface-covering undergoing cleaning up into contact with the lips of the nozzle and into the nozzle mouth 55 between those lips. The portion of the cover-

ing between the front and the rear nozzle lips of the usual machine is bowed into the nozzle, and the pile thereof is spread apart or separated to an extent depending upon the curvature of the bowed portion. Also, in the usual suction 5 cleaner the cleaning air enters the nozzle between two surface-contacting lips which define the sides of the nozzle and of the bowed portion of the covering. The pile of the covering at the points of contact of these usual nozzle lips is not separated as is the case of the pile near the center of the bowed portion. The cleaning air, in passing under the nozzle lips fails to gain entrance to the deeply embedded 10 foreign matter in the operation of the common 15 cleaner.

In the suction cleaner constructed in accordance with the present invention the usual cleaner nozzle has been divided into two parts. The portion of the nozzle containing the cleaner agitator has been separated from the remainder of the nozzle, and air is drawn from the latter under a dividing lip which separates the two portions 20 of the nozzle. There are in fact two nozzles. The common lip is so positioned that it contacts 25 the surface-covering where it is bowed and where the pile is separated. The cleaning air which passes under this lip from the low to the high suction nozzle is directed to the deeply embedded 30 foreign matter, the lip being resiliently mounted 35 in order not to restrict the lifting of the covering.

Referring now to the drawing a suction cleaner is shown in which an ordinary nozzle casting 1 is seen to be divided into two nozzles, 2 and 3. These nozzles have a common surface-contacting lip 4 which is resiliently urged downwardly by means of an elongated spring 5 carried by the common wall 6 of the two nozzles. The front lip of the nozzle casting 1, indicated by the reference character 7, is the front lip of the nozzle 2. 40 Lip 7 is extremely thin and is of the pile-penetrating type, as is the lip 4. The rear lip 8 of the casting 1 is the rear lip of the nozzle 3 and is relatively broad.

A fan chamber 9 is positioned immediately the 45 adjacent nozzle casting 1 and is interiorly connected thereto thru the eye 10. A rotatable fan 11 is mounted within the fan chamber 9 upon the extended end of the motor shaft 12 and functions, in the operation of the cleaner, to create 50 a reduced pressure within the fan chamber which is effective to draw cleaning air from the nozzle 2, through the inlet 10 into the chamber, and exhaust it into the dust bag 15. The extremity of the motor shaft 12 is formed as a pulley 13 and 55

is positioned within a housing $1a$ in the casting 1 , which housing is open to the nozzle 3 , but is sealed from nozzle 2 . It is clear that the suction of the nozzle 3 is dependent upon the amount of air drawn therefrom and under the common lip 4 into the nozzle 2 .

The suction-creating fan 11 is driven by an ordinary motor which is positioned within the motor casing 14 immediately adjacent fan chamber 9 . The motor proper is not shown, being of any well known type.

As in the usual suction cleaner front and rear supporting wheels 16 and 17 are provided which movably support the cleaner upon the surface-covering. Height-adjusting means 18 are provided for the front wheels 16 by the use of which the height of the nozzle lips above the surface covering can be controlled. A pivoted handle 19 is also provided which supports the upper end of the dust bag 15 in a common manner, which is not shown, and which provides means by which the operator can readily propel the machine over the surface-covering undergoing cleaning.

Rotatably mounted within the nozzle 3 upon the longitudinally extending stationary shaft 20 is the rotatable agitator 21 comprising an elongated cylindrical body provided upon its surface with rigid surface-contacting beating elements and flexible brush elements. Agitator 21 is formed substantially midway of its length with a pulley surface 22 which receives a power-transmitting belt 23 which is connected to the pulley 13 formed upon the motor shaft 12 . Obviously in the operation of the machine the agitator is rotated by the driving motor and contacts the lifted surface covering between the lips 4 and 8 to dislodge the embedded foreign matter therefrom.

In the operation of the suction cleaner constructed in accordance with the present invention the suction created by the fan 11 in the operation of the machine creates a reduced pressure in the nozzle 2 , which is effective, in a more limited degree, within the nozzle 3 . The surface covering positioned immediately under the nozzles is lifted by this reduced pressure into contact with the lip 7 , the lip 4 , and the lip 8 . The lip 4 being resiliently urged downwardly by the spring 5 with a force of the magnitude of the upward force exerted by the lifted covering, is moved upwardly by the covering, permitting it

to form a bowed curve between the lips 7 and 8 in which the pile is spread apart. Air entering the nozzle 2 under the lip 4 of necessity passes through the pile of the surface covering as the lip extends therein. The agitator 21 is driven by the power-transmitting means described and dislodges the embedded foreign matter from the surface-covering portion which is held thereagainst by the suction within the nozzle 3 . The suction in nozzle 3 need only be sufficiently great to perform a lifting function to hold the covering against the agitator. The nozzle 2 is unprovided with positively driven agitating means and, therefore, the higher suction which is present therein is desirable.

I claim:

1. In a suction cleaner, suction-creating means, a first nozzle, a second nozzle, an agitator in said second nozzle, said suction-creating means functioning to draw air from said nozzles in the operation of the cleaner, a common lip between said nozzles movably mounted, and means resiliently urging said lip into contact with the surface covering with a force of the magnitude of the force exerted by the suction-lifted surface covering which it contacts.

2. In a suction cleaner, suction-creating means, a high suction nozzle, a low suction nozzle, said means functioning to draw air from said nozzles in the operation of the cleaner, a movable surface-contacting lip between and common to said nozzles, and resilient means urging said lip into contact with a surface covering undergoing cleaning.

3. In a suction cleaner, suction-creating means, a high suction nozzle, a low suction nozzle, said means functioning to draw air from said nozzles in the operation of the cleaner, a lip common to said nozzles mounted to yield upwardly to permit a surface covering undergoing cleaning to be bowed into said nozzles, and means resistingly opposing the upward movement of said lip.

4. The construction set forth in claim 3 characterized in that a rotary agitator is positioned in said low suction nozzle.

5. The construction recited in claim 3 characterized in that said low suction nozzle is connected to the suction-creating means through said high suction nozzle only.

WILLIS F. HUDSON. 50
